UNITED STATES PATENT OFFICE.

GIOVANNI SAPEGNO, OF GENOA, ITALY.

RAILWAY-TIE.

1,143,442.

Specification of Letters Patent. Patented June 15, 1915.

Application filed April 8, 1913. Serial No. 759,715.

To all whom it may concern:

Be it known that I, GIOVANNI SAPEGNO, subject of the King of Italy, residing at Portici XX. Settembre 29, Genoa, Italy, have invented new and useful Improvements in Railway-Ties, of which the following is a specification.

The object of the present invention is an improved, reinforced-concrete tie or sleeper. According to the present invention the improved tie consists of a lattice beam of uniform resistance, expanded at its ends so as to furnish large supporting surfaces for the rails. Said supporting surfaces are so shaped as to provide a connection between the sleepers and the rails, their sole plates or chairs which is resilient to a certain extent, said connection being designed so as to allow the rails to be readily removed and also to be displaced so as to admit of the variations of gage depending upon the superelevation of the outer rail, of the change of some parts of the permanent way, and so on.

The accompanying drawings show, by way of example only, some of the constructional forms of the improved tie.

Figure 1 is a side elevation partly in section. Fig. 2 a plan view, partly in section. Fig. 3 is a section on an enlarged scale on line X—X, Fig. 1. Figs. 4 and 5 are, respectively, an elevation partly in section, and a plan view partly in section of a modification. Fig. 6 is an enlarged section on line X'—X', Figs. 4 and 7. Figs. 7 and 8 are, respectively, an elevation partly in section, and a plan view partly in section, of a further modification of the improved tie.

In all of said figures —a— is the lattice-beam of reinforced concrete or cement, which in the case of Figs. 1 and 4 has a parabolic upper chord.

—b— are the enlarged ends thereof offering an extended base to the railway track.

According to Fig. 1 the rail and its sole plate are laid upon lugs —c— of reinforced concrete while according to Figs. 4 and 7 they rest upon projecting brackets —d— on the upper ends of posts —e— of reinforced concrete. Both the lugs and the brackets are so dimensioned as to afford them the highest degree of elasticity consistent with the required resistance to stresses. In both cases ample recesses —f— are provided underneath for screwing and unscrewing the nuts of the bolts *g*, thus allowing the rail and its sole-plate to be se-

cured in place or readily removed if required, the recesses extending at their ends through the opposite side faces of the tie and being permanently open throughout their entire extent. The holes provided in the aforesaid lugs or brackets admit of the position of the bolts being varied to a certain extent.

Having now particularly described and ascertained the nature of my said invention and in what manner the same is to be performed, I declare that what I claim is:

1. A railway tie embodying a lattice beam of reinforced concrete provided with rail-supporting surfaces and with a connecting portion therebetween, said beam having a uniform cross-sectional resistance throughout.

2. A reinforced concrete tie having its ends enlarged and formed with transverse recesses, said recesses extending through the opposite side faces of the tie, the recesses being permanently open throughout their entire extent.

3. A railway tie embodying a lattice beam of reinforced concrete having enlarged, resilient end portions, said beam having a uniform cross-sectional resistance throughout.

4. A reinforced concrete tie provided at its ends with integral, projecting horizontal lugs to form supporting surfaces for the rails, said tie having transverse recesses beneath said lugs which extend through the opposite side faces of the tie and are permanently open throughout their entire extent, said recesses affording access to the fastening bolts and nuts.

5. A reinforced concrete tie provided at its ends with integral, vertical posts having integral horizontal brackets on the upper ends thereof to form supporting surfaces for the rails, said tie having transverse recesses beneath said brackets which extend through the opposite side faces of the tie and are permanently open throughout their entire extent, said recesses affording access to the fastening bolts and nuts.

6. A reinforced concrete tie provided at its ends with integral, horizontal supporting surfaces for the rails, said tie having transverse recesses beneath said surfaces which extend through the opposite side faces of the tie and are permanently open throughout their entire extent, said recesses affording access to the fastening bolts and nuts.

7. A reinforced concrete tie having its

ends enlarged and formed with transverse recesses whose top and bottom walls are remote from the top and bottom faces of the tie, said recesses extending through the opposite side faces of said tie and being permanently open throughout their entire extent.

In testimony whereof I hereunto affix my signature in the presence of two witnesses.

ING. GIOVANNI SAPEGNO.
